UNITED STATES PATENT OFFICE.

MATTHIAS W. JELINEK, OF BLACKHAWK, COLORADO.

SAFETY CAGE-CHAIR.

SPECIFICATION forming part of Letters Patent No. 686,658, dated November 12, 1901.

Application filed April 3, 1901. Serial No. 54,194. (No model.)

To all whom it may concern:

Be it known that I, MATTHIAS W. JELINEK, a citizen of the United States of America, residing at Blackhawk, in the county of Gilpin 5 and State of Colorado, have invented certain new and useful Improvements in Safety Cage-Chairs; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 My invention relates to improvements in safety cage-chairs for mining-shafts, and may be considered an improvement on the construction set forth in United States Letters Patent No. 667,780, dated February 12, 1901; 20 and to these ends my present invention consists of the features, arrangements, and combinations hereinafter described and claimed, all of which will be fully understood by reference to the accompanying drawings, in 25 which is illustrated an embodiment thereof.

In the drawings, Figure 1 is a vertical section taken through a cage equipped with my improved chair-dogs. Fig. 2 is a top view of the construction, partly shown in section, the 30 rail being omitted for convenience of illustration. Fig. 3 is an elevation of the cage, taken at right angles to Fig. 1. Fig. 4 is a vertical section taken through the cage, illustrating the means for simultaneously operating 35 the two sets of chair-dogs. Fig. 5 is a perspective view in detail of one of the chair-dogs.

The same reference characters indicate the same parts in all the views.

40 Let the numeral 5 designate a cage, to whose bottom 6 on the under surface are secured two parallel pieces of channel-iron 7, one being located on each side. At each end of the cage, or the sides adjacent the drifts or tunnels, are 45 located two chair-dogs 8. Each of these dogs is mounted on a short shaft 9, supported by the flanges 7^a of the channel-iron members. Each pair of dogs adjacent the same side of the cage is connected with a central rock- 50 shaft 10 by an arm 12 and connecting-rods 13. The arm 12 is fast on the shaft 10, which is operated by a lever 14, located at one side of

the cage. Each dog is provided with a depending lug 8^a, with which the outer extremity of the rod 13 is connected. The rear part 55 of the dog, or that shown at the left in Fig. 8, is provided with an opening 8^c, through which the shaft 9 passes. On each side of the body of the dog is located a lug 8^d, adapted to engage the bottom of the cage and lock the dog 60 against further movement when in the cage-supporting position, as shown in Figs. 1 and 2. The forward extremity 8^e of the dog occupies a higher plane than its rear part, and a shoulder 8^h is formed on the dog, adapted 65 to engage the bottom of the cage and co-operate with the lugs 8^d in locking the dog against further movement. The bottom of the cage is slotted between the lugs 8^d to allow the part 8^e of the dog to pass through. The part 8^e 70 of each dog forms a continuation of the rail 15 on the bottom of the cage and is adapted to engage the timbers 16 at each station or level. It is evident, however, that the dogs may be located out of line with the rails, if 75 desired. They may also be used to equal advantage on cages not provided with rails.

If it is desired to stop the cage when descending, it is only necessary to throw the dogs outwardly to the position shown in Figs. 80 1 and 2 and they will catch on the timbers 16 at the first level below. After stopping, in order to start, it is necessary first to raise the cage sufficiently to allow the dogs 8 to swing down to a vertical position, as shown 85 by dotted lines at the left of Fig. 1. The cage may then move downwardly without obstruction until it is desired to stop again. If it becomes necessary to land the cage when ascending, the cage must be allowed to pass 90 above the landing in its upward movement in order to give the dogs an opportunity to swing outwardly. As soon as this is done the cage is allowed to descend until the dogs engage the timbers 16 or other support. 95

Having thus described my invention, what I claim is—

1. The combination of a cage, whose bottom is provided on each side with a piece of channel-iron, dogs movably mounted on the 100 channel-iron flanges and arranged to project outwardly to engage a support at the stations or levels, the channel-iron members and the bottom of the cage being slotted to allow the

upper portion of each dog to pass through whereby the dogs when the cage is landed, rest on a supporting-surface.

2. The combination with a cage, of chair-dogs movably mounted thereon, the bottom of the cage being slotted at the ends to allow the upper part of the dogs to pass through, the arrangement being such that the dogs are adapted to support the cage while resting on a supporting-surface, each dog having a lug on each side adapted to engage the bottom of the cage on each side of the slot, whereby the dog is locked against further upward move-

ment after it has reached a horizontal position.

3. As an improved article of manufacture, a chair-dog having a pivot opening in its rear portion, a lug on each side, and an extension projecting beyond and occupying a plane above the side lugs.

In testimony whereof I affix my signature in presence of two witnesses.

MATTHIAS W. JELINEK.

Witnesses:

W. A. BRITTELL,
LOUIS H. RACHOPKY.
